United States Patent Office

Des. 195,151
Patented Apr. 30, 1963

195,151

CONTAINER LID

Robert E. Marsh, Los Alamitos, Calif., assignor to Engineered Plastics Container Company, Inc., Anaheim, Calif., a corporation of California

Filed Sept. 17, 1962, Ser. No. 71,714

Term of patent 7 years

(Cl. D58—26)

Fig. 1

Fig. 3

Fig. 2

Fig. 4

Fig. 5

FIG. 1 is a top perspective view of a container lid showing my new design;
FIG. 2 is a front elevation thereof;
FIG. 3 is a side elevation thereof;
FIG. 4 is a top plan view thereof; and
FIG. 5 is a sectional detail along the line 5—5 of FIG. 4;

I claim:

The ornamental design for a container lid, substantially as shown.
